Primary Examiner — John A Voytek(74) *Attorney, Agent, or Firm* — Birch, Stewart, Kolasch & Birch, LLP(57) **CLAIM**

The ornamental design for a tire for motorcycle, as shown and described.

DESCRIPTION

FIG. 1 is a front view of a tire for motorcycle showing my new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a partial enlarged view of portion 7A-7B thereof;

FIG. 8 is an enlarged end elevational view taken along line 8-8 of FIG. 7;

FIG. 9 is an enlarged end elevational view taken along line 9-9 of FIG. 7; and,

FIG. 10 is an enlarged end elevational view taken along line 10-10 of FIG. 7.

The portions of the drawings illustrated in broken lines are directed to the environment of the design and form no part of the claimed design.
